LOADER MECHANISM

William A. Morton and Carl A. Nielsen, Pittsburgh, Pa., assignors to Amco, Incorporated, Pittsburgh, Pa., a corporation of Pennsylvania

Application March 3, 1933, Serial No. 659,524

20 Claims. (Cl. 198—31)

More particularly our invention is designed as a lehr loader for glassware and the like.

In designing an efficient lehr loader certain problems are to be met.

5 Thus the buck or conveyer which transports the ware from the fabricating machines to the lehr is adjusted to the proper height to suit the take-out of the particular fabricating machine or to suit the set-up of the machine for the fabrication of a given type or length of the bottles or other glassware. Therefore the loader must be adjustable to enable it to transfer ware from bucks set at different elevations to the transport conveyer of the annealing lehr.

10 Again, in modern practice the operative speeds of the fabricating machines have been materially increased and therefore the bottles or other ware are delivered by the buck at greater speed and with reduced intervals, so that the loader must work more rapidly and with greater accuracy 20 to properly perform its function.

Moreover owing to the increased speed of removal from the buck, it is necessary to support the ware against toppling while the ware is being removed from the buck and also while it is being transferred to and arranged on the lehr conveyer.

25 Again, frequently the ware as received from the buck is only partially set or hardened and therefore must not be pinched by the loader mechanism, nor should it be moved in contact with extended supporting surfaces during the loading operation. Otherwise the ware is likely to be deformed or marred.

These problems are fully solved by our improved loader mechanism.

30 A characteristic feature of our improved loader mechanism is a movable shelf which is disposed in juxtaposition with the delivery portion of the buck to receive a selected number of articles therefrom and is then moved into discharge relation with the lehr conveyer for the deposit of the articles on the lehr conveyer. We provide a holder for transferring the ware from the buck to the shelf, for supporting the ware from toppling, and also for assisting in depositing the ware from the shelf in proper arrangement on the lehr conveyer. The preferred form of the holder is a pair of parallel holder bars.

35 The shelf is arranged for both vertical and horizontal movement as is likewise the holder, provision being made for movement of the shelf and holder both in unison and independently of each other.

50 Other novel features of construction, and also

of arrangement of parts, will appear from the following description.

In the accompanying drawings, wherein we have illustrated a practical embodiment of the principles of our invention, Fig. 1 is an isometric projection showing the loader in receiving relation to the buck.

55 Fig. 2 is a like view showing the loader moved from its position in Fig. 1 into discharge relation to the lehr conveyer.

60 Fig. 3 is a diagrammatic view showing the timer cams, valves and air cylinders, and their connections.

65 Fig. 4 is an enlarged detail partially in section showing one of the timer cams and a poppet valve arranged to be operated thereby.

70 Fig. 5 is a still further enlarged detail showing the adjustable cam structure.

75 Fig. 6 is a sectional view of the same taken in a plane at right angles to that of Fig. 5.

80 Fig. 7 is a diagrammatic view illustrating the relation of the shelf, the holder and the buck before the holder is depressed to the ware on the buck.

85 Fig. 8 is a similar view illustrating the holder depressed.

90 Fig. 9 illustrates the holder closed about the ware on the buck.

95 Fig. 10 illustrates the holder moved horizontally to transfer the ware from the buck to the shelf.

100 Fig. 11 illustrates the holder and the shelf with the ware elevated above the buck.

105 Fig. 12 illustrates the holder, the shelf and the ware on the shelf moved over above the receiving end of the lehr conveyer.

110 Fig. 13 illustrates the shelf moved horizontally away from the conveyer to permit the ware previously on the shelf to be deposited in a row on the conveyer.

115 Fig. 14 illustrates the holder elevated above the deposited ware preliminary to swinging the loader back into the position as illustrated in Fig. 7.

120 Referring to the drawings, 1 represents a buck or conveyer which delivers the ware from the fabricating machine or machines, the ware being illustrated as bottles. The take-out of a fabricating machine is illustrated at 2 as depositing a bottle on the buck 1. The belt of the buck is assumed to be traveling from left to right in Fig. 1. 3 represents the stationary side rails for the buck level with its top surface.

125 4 represents the lehr provided with a conveyer 5 which is shown as of the wire-mesh type. The ware to be annealed is arranged in transverse

rows on the lehr conveyer in accordance with the usual practice.

The moving parts of the loader are carried on a fixed support which may be conveniently 5 of rectangular form and comprising a vertical column 6 and a horizontal base portion 7 extending rearwardly. 8 and 9 represent upper and lower horizontal brackets extending forwardly from the column 6 and provided at their 10 outer ends with collars in which are journalled the upper and lower gudgeons of the main frame of the loader which comprises the upper cross-head 10, lower cross-head 11 and vertical connecting rods 12. The frame is thus arranged to 15 swing on a vertical axis which is coincident with the center line of the frame.

13 and 14 represent, respectively, upper and lower double-acting cylinders which are provided with sleeve-guides which are slidably 20 mounted on the rods 12.

The upper cylinder 13 is closed at its upper end and its piston 15 is provided with a rod 16 which extends through a gland in the lower end of the cylinder 13 and is fixed at its lower end to 25 the cylinder 14.

Thus we have shown the piston rod attached to a cross bar 17 which connects the sleeve-guides of the cylinder 14.

The piston 18 of the cylinder 14 is provided 30 with a depending piston rod 19 which extends through a gland in the lower end of the cylinder and is fixed to the center of the lower cross-head 11.

20 represents an abutment bolt screwed through 35 the upper end of the lower cylinder 14 and arranged to impinge against the piston to adjustably limit the descent of the cylinder relative to the main frame.

21 represents a pair of parallel and horizontally 40 disposed bars fixed to and extending forwardly from the sleeve-guides of the lower cylinder 14. 22 represents a frame, for convenience termed the shelf-frame, which is mounted on the rods 21 and arranged to slide transversely 45 of the latter in a horizontal plane. Thus the end rods of the shelf-frame may slide in sleeves 23 carried by the rods 21.

For the purpose of moving the shelf-frame 22 relative to its supporting rods 21, a double-acting 50 cylinder 24 is mounted on the rods 21 and has its piston rod 25 connected to a suitably arranged portion of the shelf frame.

The shelf-frame is provided with the depending 55 legs 26 to the lower ends of which is fixed the horizontally disposed shelf 27.

28 represents a pair of parallel and horizontally 60 disposed rods fixed to and extending forwardly from the sleeve-guides of the upper cylinder 13, and 29 represents a frame, for convenience termed the holder-frame, mounted on the rods 28 and arranged to slide transversely of the latter in a horizontal plane. Thus the end rods of the holder-frame may slide in sleeves 30 carried by the rods 28.

65 For the purpose of moving the holder-frame 29 relative to the supporting rods 28, we provide a double-acting cylinder 31 supported by the rods 28 and having its piston rod 32 connected to a suitably arranged portion of the frame 29.

70 33 represents two pairs of coacting tong-arms which depend from the holder-frame 29 and are pivotally supported therefrom adjacent their upper ends, as at 34. The upper ends of the members of each pair of arms are connected by toggle 75 links 35 and the pivots of the two pairs of links

are formed by the horizontally disposed rod 36 which is connected at its center to the upper end of the piston rod 37 of the double-acting cylinder 38 mounted on the holder-frame 29. 39 represents horizontally disposed holder-bars which 80 are mounted on the lower ends of corresponding members of the two pairs of arms 33.

It is obvious that when fluid pressure is admitted to the lower end of the cylinder 38 the rod is raised and the bars 39 are caused to separate, while the admission of fluid pressure to the upper end of the cylinder will cause said bars to converge.

To prevent the holder-bars from pinching the ware as they converge, we provide means for 90 adjustably limiting their converging movement. Thus, as illustrated in Fig. 3 an abutment bolt 40 may be screwed through a threaded hole in the lower end of the cylinder 38 to limit the downward travel of the piston. Thus the bars may 95 be nicely adjusted to furnish the proper lateral support for the ware without danger of pinching or otherwise injuring the ware.

41 represents a gate pivoted to the side rail 3 of the buck and pivotally connected intermediate 100 of its ends to the piston rod 42 of a double-acting cylinder 43. The gate is at intervals swung into the path of the traveling line of bottles to halt the advance while a row is being shifted from the buck to the shelf.

For the purpose of swinging the main-frame as hereinafter described a cylinder 44 is mounted on the base 7 and its piston rod 45 is provided with a rack 46 which meshes with a pinion 47 mounted on the lower gudgeon of the main frame 110 below the lower bracket 9.

As has been indicated by the foregoing description, we prefer to operate our lehr loader by fluid pressure means, but it is obvious other methods of operation may be substituted.

In Fig. 3 we illustrate a practical and convenient arrangement for fluid pressure operation and control. Thus 48, 49, 50, 51, 52, 53 and 54 represent piston valves of a type in common use in the glass fabricating art. Said valves are all 120 supplied with compressed air by the branched pipe 55, and are employed to control the operation of the cylinders.

The cylinder ports of the valve 48 are connected to the opposite ends of the cylinder 31 125 by the pipes 31a and 31b respectively. The like ports of the valve 49 are connected to the opposite ends of the valves 38 by the pipes 38a-38b, respectively. The like ports of the valve 50 are connected by the pipes 13a and 13b to the opposite ends of the cylinder 13. The like ports of the valve 51 are connected to the opposite ends of the cylinder 24 by the pipes 24a and 24b, respectively. The like ports of the valve 52 are connected to the opposite ends of the cylinder 14 by the pipes 14a and 14b, respectively. The like ports of the valve 53 are connected to the opposite ends of the cylinder 44 by the pipes 44a and 44b, respectively. The like ports of the valve 54 are connected to the opposite ends of the cylinder 43 by the pipes 43a and 43b respectively.

56 represents a battery of poppet valves mounted in a common support 57. Compressed air is supplied to said poppet valves by a passage 58 connected to the pipe 55. The valves are 145 connected in pairs to the opposite ends of the several valves in the usual manner as shown in Fig. 3. Thus the pipes 48a and 48b connect the opposite ends of the valve 48 to adjacent poppet valves. In like manner similarly indicated pipes 150

connect the opposite ends of each of the other control valves to a pair of adjacent poppet valves.

The poppet valves are actuated by means of strikers 59 adjustably mounted on disks 60 which

5 in turn are mounted on the timer shaft 61 driven through the speed reducer 62 by the motor 63. As indicated in the drawings the strikers are adjustable about their respective disks so that the proper relative timing of the actuation of the various poppet valves may be obtained.

The operation of the poppet valve is well known in the art, the arrangement being such that when the poppet valve is momentarily opened by the striker, compressed air is admitted to the corresponding end of the control valve and the valve piston is forced to the opposite end of the casing admitting pressure to the corresponding end of the cylinder to which the control valve is coupled. When the poppet valve is idle the corresponding connecting pipe is open to atmosphere, thereby relieving pressure from the corresponding end of the control valve.

The normal operation of our improved loader is illustrated by Figs. 7 to 14 inclusive. Thus in 25 Fig. 7 the loader is shown in receiving position, the main frame being swung into the position shown in Fig. 1 with the shelf parallel with and adjacent the side rail 3 of the buck 1. The shelf is leveled with the buck at its lowered position by 30 the proper adjustment of the abutment bolt 20 in the head of the cylinder 14. As will be seen the shelf-frame 22 and the shelf are lowered by the admission of fluid pressure in the lower end of the cylinder 14, causing it to descend relative 35 to its stationary piston and thus by properly adjusting the bolt 20 the shelf in descending will halt at the proper level.

Still referring to Fig. 7 the holder-frame 29 is shifted to the left relative to the main frame so 40 that the tong-arms and holder bars are above the row of bottles on the buck, the holder-frame having been previously elevated by the admission of fluid pressure into the upper end of the cylinder 13. The holder-bars 39 have also been spread 45 apart by the admission of fluid pressure into the lower end of the cylinder 38.

The next step, as illustrated in Fig. 8 is the lowering of the spread holder-bars to either side of the row of bottles on the buck. The next step, 50 Fig. 9, is the convergence of the holder-bars into light contact with the row of bottles. This is accomplished by the admission of fluid pressure into the upper end of the cylinder 38. By adjusting the abutment bolt 40 in the lower end of the cylinder 55 13 the proper convergence of the holder-bars is obtained just sufficient to enable the ware to be properly manipulated while avoiding pinching or marring the ware. The next step is illustrated in Fig. 10, comprising the shifting of the row of bottles held between the holder bars from the buck onto the shelf 27. This is accomplished by the admission of fluid pressure into the left hand end of the cylinder 31, thus shifting the holder-frame 29 relative to the main frame, toward the 60 right in Fig. 1. At the proper moment, preferably as the holder-bars are lowered and just as they are caused to converge, the gate 41 is swung in front of the line of bottles traveling on the buck to temporarily halt the line. As soon as the row 65 of bottles is shifted from the buck as in Fig. 10, the gate is retracted by the admission of fluid pressure into the front end of the cylinder 43.

The next step is the elevation of the shelf and holder-bars with the row of bottles to the proper level so that when the main frame is swung from

its position in Fig. 1 to its position in Fig. 2 the shelf will overlap the front end of the lehr conveyer 5 and be spaced sufficiently above the same to clear it.

By the introduction of fluid pressure into the upper end of the cylinder 14 the shelf-frame 22 and the holder-frame 29 are elevated in unison, thus elevating the row of bottles resting on the shelf, as illustrated in Fig. 11. The next step is the swinging of the main frame into its position illustrated in Fig. 2. This is accomplished by the introduction of fluid pressure into the rear end of the cylinder 44. As shown in Fig. 12 the shelf now overlaps the receiving end of the lehr conveyer with the bottles held on the shelf by the holder-bars.

It is obvious that the elevation of the shelf and the swinging of the main frame may occur simultaneously.

The next step is the retraction of the shelf from beneath the row of bottles, causing them to be deposited in proper array on the lehr conveyer, as is illustrated in Fig. 13, the bottles being held from following the moving shelf and from toppling by the stationary holder-bars. The shelf is shifted by the admission of fluid pressure in the rear end of the cylinder 24.

The next step is the elevation of the holder-bars above the deposited row of bottles. This is illustrated in Fig. 14 and is accomplished by the introduction of fluid pressure into the upper end of the cylinder 13, thus elevating the holder-frame 29. If desired the holder bars may be started to diverge before being elevated but care must be observed not to touch or topple the adjacent rows of bottles on the lehr conveyer. This divergence is accomplished by introducing fluid pressure into the lower end of cylinder 38.

The next step is the introduction of fluid pressure into the front end of the cylinder 44, thus 115 swinging the main frame from its position in Fig. 2 to its position in Fig. 1. The next step is the lowering of the shelf 27 to the level of the buck which is accomplished by the introduction of fluid pressure into the lower end of cylinder 14. 120

Simultaneously fluid pressure is introduced into the upper end of cylinder 13, thus preventing this cylinder from moving downwardly with the cylinder 14. Thus while the shelf is lowered the holder-bars remain elevated. The holder-bars 125 are then shifted to the left so as to be poised above the path of the ware on the buck. This is accomplished by the introduction of fluid pressure into the rear end of the cylinder 31.

It is obvious that the shelf may be lowered and 130 the holder-bars shifted relative thereto while the main frame is being swung into its position shown in Fig. 1.

It is evident that the holder-frame must be 135 capable of greater horizontal movement relative to the main frame than the shelf-frame. This may be conveniently provided for by making the cylinder 31 longer than the cylinder 24.

The length of the shelf is governed by the effective width of the lehr conveyer so that a row 140 of bottles of proper length to fill the lehr conveyer is loaded thereon.

The lift of the cylinder 13 independent of its movement in unison with the cylinder 14 is sufficient to enable the holder bars to be elevated out 145 of contact with the bottles on the buck and on the lehr conveyer.

While our improved loader is especially designed for transferring bottles and other ware from a buck or delivery conveyer to and ar- 150

ranging them on a lehr conveyer, it is obvious that it may be employed for the transfer of other types of ware or articles from one conveyer to another.

5 We claim:—

1. In loader mechanism for removing articles from one conveyer and arranging said articles on a second conveyer which is disposed in angular relation to the first-named conveyer, the combination of a shelf arranged for swinging movement about a vertical axis between the conveyers, holder-means associated with the shelf and arranged for movement in unison with the shelf and also independently of the shelf, and means for selectively moving the shelf and the holder-means whereby the shelf is leveled in parallelism with the first conveyer, the holder-means engages articles on the first conveyer and shifts them onto the shelf, the shelf and the holder-means are brought adjacent to the second conveyer, the articles are removed from the shelf and arranged on the second conveyer and the shelf and the holder means are returned to the first conveyer to repeat the steps.

2. In loader mechanism for removing articles from one conveyer and arranging said articles on a second conveyer which is disposed in angular relation to the first-named conveyer, the combination of a shelf arranged for swinging movement about a vertical axis between the conveyers, holder-means associated with the shelf and arranged for movement in unison with the shelf and also independently of the shelf, and means for selectively moving the shelf and the holder-means whereby the shelf is leveled in parallelism with the first conveyer, the holder-means engages articles on the first conveyer and shifts them onto the shelf, the shelf and the holder-means are brought in position above the second conveyer, the shelf is retracted from beneath the articles while they are sustained laterally by the holder-means whereby the articles are deposited on the second conveyer, the holder-means is disengaged from the deposited articles and the shelf and the holder-means are returned to the first conveyer to repeat the steps.

3. In loader mechanism for removing articles from one conveyer and arranging said articles on a second conveyer which is disposed in angular relation to the first-named conveyer, the combination of a shelf arranged for swinging movement about a vertical axis between the conveyers, holder-means associated with the shelf and arranged for movement in unison with the shelf and also independently of the shelf, and means for selectively moving the shelf and the holder-means whereby the shelf is leveled in parallelism with the first conveyer, the holder-means engages articles on the first conveyer and shifts them onto the shelf, the shelf and the holder-means are brought in position above and disposed at substantially right angles to the axis of the second conveyer, the shelf is retracted from beneath the articles while they are sustained laterally by the holder-means whereby the articles are deposited on the second conveyer, the holder-means is disengaged from the deposited articles and the shelf and the holder-means are returned to the first conveyer to repeat the steps.

4. In loader mechanism for removing articles from one conveyer and arranging said articles on a second conveyer, the combination of a shelf arranged for both vertical and horizontal movement between the conveyers, holder-means associated with the shelf and arranged for movement in unison with the shelf and also independently of the shelf, and means for selectively moving the shelf and the holder-means whereby the shelf is leveled in parallelism with the first conveyer, the holder-means engages articles on the first conveyer and shifts them onto the shelf, the shelf and the holder-means are brought adjacent to the second conveyer, the articles are removed from the shelf and arranged on the second conveyer and the shelf and the holder means are returned to the first conveyer to repeat the steps, and means for varying the elevation of the shelf to accommodate varying levels of the first conveyer.

in unison with the shelf and also independently of the shelf, and operative means arranged for selectively moving the shelf and the holder-means horizontally and vertically whereby the shelf is leveled in parallelism with the first conveyer, the holder-means engages articles on the first conveyer and shifts them onto the shelf, the shelf and holder-means are brought adjacent to the second conveyer, the articles are removed from the shelf and arranged on the second conveyer and the shelf and holder-means are returned to the first conveyer to repeat the steps.

5. In loader mechanism for removing articles from one conveyer and arranging said articles on a second conveyer, the combination of a shelf arranged for both vertical and horizontal movement between the conveyers, holder-means associated with the shelf and arranged for movement in unison with the shelf and also independently of the shelf, and operative means arranged for selectively moving the shelf and the holder-means horizontally and vertically whereby the shelf is leveled in parallelism with the first conveyer, the holder-means engages articles on the first conveyer and shifts them onto the shelf, the shelf and holder-means are brought in position above the second conveyer, the shelf is retracted from beneath the articles while they are sustained laterally by the holder-means whereby the articles are deposited on the second conveyer, the holder-means is disengaged from the deposited articles and the shelf and the holder means are returned to the first conveyer to repeat the steps.

6. In loader mechanism for removing articles from one conveyer and arranging said articles on a second conveyer, the combination of a shelf arranged for both vertical and horizontal movement between the conveyers, holder-means associated with the shelf and arranged for movement in unison with the shelf and also independently of the shelf, and operative means arranged for selectively moving the shelf and the holder-means horizontally and vertically whereby the shelf is leveled in parallelism with the first conveyer, the holder-means engages articles on the first conveyer and shifts them onto the shelf, the shelf and holder-means are brought in position above and disposed at substantially right angles to the second conveyer, the shelf is retracted from beneath the articles while they are sustained laterally by the holder-means whereby the articles are deposited on the second conveyer, the holder-means is disengaged from the deposited articles and the shelf and the holder-means are returned to the first conveyer to repeat the steps.

7. In loader mechanism for removing articles from one conveyer and arranging said articles on a second conveyer, the combination of a shelf arranged for movement between the conveyers, holder-means associated with the shelf and arranged for movement in unison with the shelf and also independently of the shelf, means for selectively moving the shelf and the holder-means whereby the shelf is leveled in parallelism with the first conveyer, the holder-means engages articles on the first conveyer and shifts them onto the shelf, the shelf and the holder-means are brought adjacent to the second conveyer, the articles are removed from the shelf and arranged on the second conveyer and the shelf and the holder means are returned to the first conveyer to repeat the steps, and means for varying the elevation of the shelf to accommodate varying levels of the first conveyer.

frame, and holder-means carried by the holder-frame.

18. In loader mechanism for removing articles from one conveyer and arranging them on a second conveyer, the combination of a main frame, means for moving the main frame between the conveyers, a shelf-frame and a holder-frame carried by said main frame and movable horizontally relative to the main frame and independently of each other, means for moving said shelf-frame and holder-frame vertically and in unison, means for moving the holder-frame vertically relative to the shelf-frame, article-holder means carried by the holder-frame, and a shelf carried by the shelf-frame.

19. In loader mechanism for removing articles from one conveyer and arranging them on a second conveyer, the combination of a main frame, means for moving the main frame between the conveyers, a shelf-frame and a holder-frame carried by the main frame and arranged for move-

ment relative to the main frame both in unison and independently, a shelf carried by the shelf-frame, holder-means carried by the holder-frame, said holder-means comprising tong-arms, and means for causing said tong-arms to converge 80 and to diverge.

20. In loader mechanism for removing articles from one conveyer and arranging them on a second conveyer, the combination of a main frame, means for moving the main frame between the conveyers, a shelf-frame and a holder-frame carried by the main frame and arranged for movement relative to the main frame both in unison and independently, a shelf carried by the shelf-frame, holder-means carried by the holder-frame, 85 said holder-means comprising tong-arms pivotally mounted on the frame, and means for causing the tong-arms to converge and to diverge. 90

WILLIAM A. MORTON. 95
CARL A. NIELSEN.
